UNITED STATES PATENT OFFICE.

CHARLES B. MORROW, OF CHICAGO, ILLINOIS, ASSIGNOR TO THE GREAT WESTERN WIRE WORKS COMPANY, OF SAME PLACE.

DESIGN FOR A DISPLAY-STAND.

SPECIFICATION forming part of Design No. 22,538, dated June 13, 1893.

Application filed April 17, 1893. Serial No. 470,764. Term of patent 7 years.

To all whom it may concern:

Be it known that I, CHARLES B. MORROW, a citizen of the United States, residing at Chicago, in the county of Cook and State of Illinois, have invented and produced a new and original Design for a Display-Stand, of which the following is a specification, reference being had to the accompanying drawings, forming part thereof.

10 Figure 1 is a side elevation of my display stand. Fig. 2 is a transverse section taken on the line 2. 2. of Fig. 1, in which a top or plan view of the sleeve with wire branches attached, and of the base plate are shown.

15 The noticeable or leading feature of my design consists in the pointed crescent shaped wire branches, which are attached about midway of their length to sleeves, a series of which is mounted upon an upright standard or rod 20 fixed to and supported upon a suitable base plate. Said rod or standard is provided with a cap or top piece to give a finished appearance thereto. The points of the crescent shaped wire branches extend outward from 25 the standard rod, and are sharpened or re-

duced in thickness the ensemble forming a pleasing design.

Referring to the drawings, 1 designates the base plate casting, which in its general outline or contour is circular, but which is scalloped at its lower edge and provided with feet projecting therefrom, and is given a more or less ornate appearance as shown in the drawings.

2 is the standard rod, 3 is the cap or top 35 piece, 4 the sleeves and 6 the crescent shaped wire branches.

What I claim is—

The design for a display stand herein shown and described the same comprising the base 40 plate 1, the standard rod 2, the cap-piece 3, the sleeves 4, and the crescent-shaped wire branches 6, as set forth.

In testimony whereof I affix my signature in presence of two witnesses.

CHARLES B. MORROW.
